UNITED STATES PATENT OFFICE

REMUS KOENIG, OF TWO RIVERS, WISCONSIN, ASSIGNOR TO METAL WARE CORPORATION, OF TWO RIVERS, WISCONSIN

TOY ELECTRIC ENGINE

Application filed August 9, 1928. Serial No. 298,480.

This invention relates to a toy electric engine.

Objects of this invention are to provide a novel form of toy electric engine which is so constructed that it may be connected with the usual lighting system employing alternating current, and is provided with a transformer for reducing the voltage, a switch being provided in the secondary circuit for 10 the manual control of the engine, so that when a child plays with the engine, he will not be endangered under any possible condition, as the low voltage side of the transformer is the only one leading to the contacts and to the 15 manually controlled switch.

Further objects of this invention are to provide an engine so constructed that the transformer is positioned within a boiler-like shell, open top and bottom, to thus ventilate the transformer, and in which a single, simple type of casting is employed for the engine body and is secured to the base thereby eliminating any necessity for machining the base.

25 An embodiment of the invention is shown in the accompanying drawings in which:

Figure 1 is a plan view of the device with parts broken away;

Figure 2 is a side elevation partly in section;

Figure 3 is a diagrammatic view showing the wiring.

Referring to the drawings, it will be seen that the device comprises a base plate 1

35 which may be provided with suitable legs and which carries an engine body 2. This engine body 2 revolvably supports the shaft 3, which carries the flywheel 4, and also carries a pair of spaced electromagnets 5 which are positioned within a housing-like portion 6. This unit also carries an insulating block

7 which has a pair of ribs 8 through which contacts 9 project. These contacts are slideable within the apertures through the ribs 8

45 and are urged inwardly by means of the springs 10. They are adapted to engage contacts carried by the lower end of the rock arm 11 which engages one or the other of the contacts as it rocks back and forth. Motion is imparted to the rock arm by means of

the link 12 which passes around an eccentric carried on the shaft 3.

The shaft 3 is provided with a crank pin 13 at one end which is connected by means of a link 14 with a lever 15. This lever 15 is, in reality, an armature and is located between the poles of the magnets 5. It is pivoted adjacent its lower end, to downwardly projecting tongues 16 formed integrally with the engine body 2. For example, the tongues 16 may be integral with the box-like portion 6 of the engine body which carries the magnets 5, as shown most clearly in Figure 2. This box-like body is provided with a top 17 which, in turn, carries a cylinder-like member 18 into which the link 14 passes.

To further simulate a steam engine, the device may be provided with a toy governor 19 connected by means of a belt with the shaft 3. The base plate 1 carries a boiler-like shell 19. The base is open below the boiler, and the top of the boiler is surmounted by means of a chimney 20. The boiler-like shell is provided with a plurality of apertures 21 so that air may freely pass through the boiler-like shell and thus cool the transformer.

The base 1 is also provided with a manually operable switch 22 which is connected in the secondary circuit, as will hereinafter appear.

80 The transformer referred to above is indicated by the reference character 23 and is, as stated, located within the boiler-like shell 19.

85 Referring to Figure 3, it will be seen that the transformer indicated generally by the reference character 23 has its secondary 24 connected in circuit with the magnets 5 and with the automatic contacts previously described and also in series with the manually operable switch 22.

The arm or lever 11 which constitutes the automatic switch lever is connected to one side of the switch 22. The relatively stationary contacts 9 are connected to opposite pairs of the magnets 5.

90 It will be seen that as the lever 11 rocks first one pair of magnets is energized and thereafter the other, thus imparting a rocking motion to the armature and through the 100

medium of the link 14, rotating the shaft 3 and thus driving the flywheel. If desired, it is apparent that the shaft 3 may be provided with a small pulley 25 from which power may be taken.

5 It will be seen that a simple, easily constructed electric engine has been provided by this invention, which is safe for operation by a child, and which has only the low voltage side of the transformer connected to the switch and to the contacts.

10 It will be seen also that the device is easily assembled, as the engine body and the associated parts may be assembled as a unit and thereafter secured to the base.

15 Although the invention has been described in considerable detail, such description is intended as illustrative rather than limiting as the invention may be variously embodied 20 and as the scope of such invention is to be determined as claimed.

I claim:

25 1. A toy electric engine comprising a base plate, an engine body, a shaft revolvably carried by said engine body, a flywheel carried by said shaft, a crank and eccentric carried by said shaft, an electromagnetic device having a movable armature connected by means of a link with said crank, contacts carried by said engine body and connected to said electromagnetic device, a rocking switch lever cooperating with said contacts, and means for rocking said switch lever from said eccentric, said engine body and the parts 30 carried thereby forming a unit and said engine body being removably secured to said base.

35 2. A toy electric engine comprising a revolvably mounted shaft provided with a flywheel and a crank, a lever pivoted at one end and having its other end operatively connected to said crank, electromagnets located upon opposite sides of said lever, an insulating block having a pair of spaced ribs, contacts connected to said electromagnets and 40 slidably carried by the said ribs, a rocking lever cooperating with said contacts, and means driven from said shaft for rocking said last mentioned lever.

45 50 In testimony that I claim the foregoing I have hereunto set my hand at Two Rivers, in the county of Manitowoc and State of Wisconsin.

REMUS KOENIG.
